UNITED STATES PATENT OFFICE.

SETH WHEELER, JR., OF CASTLETON, NEW YORK.

PAPER PACKAGE.

No. 910,756.

Specification of Letters Patent.

Patented Jan. 26, 1909.

Application filed October 12, 1908. Serial No. 457,248.

To all whom it may concern:

Be it known that I, SETH WHEELER, Jr., a citizen of the United States of America, and a resident of Castleton, county of Rensselaer,

5 State of New York, have invented certain new and useful Improvements in Paper Packages, of which the following is a specification, reference being had to the accompanying drawings, forming a part thereof.

10 My invention relates to improvements in paper packages and particularly to paper packages composed of a plurality of units each comprising one or more sheets having one or more folds therein whereby two or 15 more leaves are formed, the leaves of adjacent units being interfolded.

This form of package is employed in a cabinet with the first leaf of the lowermost end unit of a package projecting through a delivery slot. By pulling upon this unit, the 20 said unit is withdrawn and at the same time the first leaf of the next succeeding unit, which then becomes the end unit of the package, is drawn out through the delivery opening and 25 exposed for the next withdrawing operation.

As a package becomes partly used up it is desirable to recharge the cabinet with another package so that when the last unit of any one 30 package has been withdrawn, the first or end unit of the new package shall be ready for withdrawal. This may, of course, be effected by the interleaving of the adjacent terminal leaves of the two packages, but such an operation is somewhat difficult to accomplish and 35 requires some dexterity to effect.

In my present invention, I have provided a means whereby it is only necessary to insert the new package in the cabinet, permitting it to rest upon the remainder of the partially used package, without any interleaving of the terminal units of the two packages, in order that the new package may be available for use directly the old package has been entirely used up. This means comprises a terminal unit formed of a single sheet of paper preferably somewhat thicker than the paper ordinarily employed in the units, the said unit having an end leaf of a length less than the length of the leaves of the ordinary units, 40 this short end leaf arranged to project over the edge of the remaining portion of the package contained in the cabinet and so to be concealed thereby until the balance of the former package is completely used up. When 45 the last sheet of such package is removed, this end leaf or leader, as I term it, will be ex-

posed to view and the first sheet of the new unit may be readily introduced through the delivery opening by the manipulation of this terminal element.

In order that my invention may be fully understood, I will now proceed to describe an embodiment thereof, having reference to the accompanying drawings, and will then point out the novel features in claims.

In the drawings: Figure 1 is a view in perspective of a package constructed in accordance with my invention. Fig. 2 is a view in transverse section through a cabinet containing portions of two packages, one being the remainder of a package which has been partially dispensed and the other the lower portion of a new package. Fig. 3 is a view in perspective of one of the leader elements removed from the package. Fig. 4 is a view in perspective of two of the units of which the package, as a whole, is composed, showing their construction and the manner in which they are interfolded.

The units composing the package illustrated in the drawing herein comprise each two sheets, *a* and *b*, each sheet folded backwards upon itself twice as at *c* so as to form three leaves, *d*, *e* and *f*. The leaves *d* and *f* are interfolded with corresponding leaves of the adjacent units, all of which will be readily understood by reference to Fig. 4 of the drawings. Fig. 4 illustrates two units partly separated, it being understood that in the final package, the leaves are pressed down close together as shown in Fig. 1.

In Fig. 3, I have shown, in perspective, a terminal element constructed in accordance with my invention. This terminal unit has three leaves *g*, *h* and *i*, the leaf *i* being very much shorter than the leaves *d*, *e* and *f* of the package units. This terminal element is interfolded with the end unit of the package, the leaf *i* being allowed to project somewhat in the manner shown in Fig. 1. When the new package is placed in the cabinet upon the remainder of the old package, this leaf *i* is allowed to project downward behind the remainder of the preceding package as is clearly shown in Fig. 2 of the drawings. The new package thus introduced into the cabinet is not interleaved in any way with the remainder of the preceding package, and the remainder of the preceding package is dispensed just as before by the simple withdrawal of the units, one by one through the delivery of the opening of the cabinet. So

long as any portion of the said preceding package remains in the cabinet, this leaf *i* will be concealed from view, and being very much shorter than the exposed leaf of any unit, there will be no danger of it being handled accidentally. When, however, the last unit of the preceding package has been removed, this leaf *i* of the next succeeding package will be exposed to view and by 10 grasping the said sheet and drawing the element, *g*, *h* and *i* through the delivery opening, the first leaf of the end unit of the new package will be drawn into place through the delivery opening so that the new package 15 will then be in a position to have its units dispensed one at a time in the required manner. I preferably form the elements *g*, *h* and *i* of a single sheet of paper of stiffer, heavier material than that of which the sheets of the 20 units are composed, and I may conveniently introduce advertising matter upon the various leaves of such elements as will be well understood. I also conveniently cut the edges of the terminal leaf *i* at an angle as is 25 shown at *j* so that the extremity thereof is considerably narrower than the width of the package. By this means, the placing of the leaf in position behind the remainder of the preceding package in the cabinet is facilitated, the user is compelled to grasp the 30 sheet near the center, and the liability of the leaf being accidentally handled while there is still any portion of the preceding package left in position, is still further reduced.

35 What I claim is:

1. A package of paper comprising a plu-

rality of folded and interfolded units, and a terminal element interleaved with the end unit, the final leaf of the said terminal element being shorter than the leaves of the 10 units.

2. A package of paper comprising folded and interfolded units and a terminal element also interfolded therein, the said terminal element composed of a heavier material than 45 the material of which the units are composed and provided with a projecting end substantially as set forth.

3. A package of paper comprising units which are folded into leaves, the leaves of adjacent units being interfolded, and provided with a terminal element having a leaf interfolded with the final leaf of the end unit, the 50 said terminal element being provided with a projecting leaf of a length less than the 55 length of the leaves of the units.

4. A package of paper comprising units which are folded into leaves, the leaves of adjacent units being interfolded, and provided with a terminal element having a leaf interfolded with the final leaf of the end unit, the 60 said terminal element being provided with a projecting leaf of a length less than the length of the leaves of the units, and having its edges cut away at an angle so that it is narrower at its end than the width of the leaves 65 of the units.
